(57) **CLAIM**

The ornamental design for a hollow ribbed hockey stick insert to fix a broken hockey stick shaft, as shown and described.

DESCRIPTION

FIG. 1 is a perspective view of a hollow ribbed hockey stick insert to fix a broken hockey stick shaft, showing my new design;

FIG. 2 is a front elevation view thereof;

FIG. 3 is a rear view thereof;

FIG. 4 is a top plan view thereof;

FIG. 5 is a bottom view thereof; and,

FIG. 6 is an end view thereof; and,

FIG. 7 is an opposite end view.

The broken line showing is included for the purpose of illustrating and forms no part of the claimed design.
